UNITED STATES PATENT OFFICE

JOHN H. DALEN, OF PIEDMONT, CALIFORNIA

WOOD-SLICING MACHINE

Application filed March 11, 1929. Serial No. 345,991.

This invention relates to wood slicing machines and particularly pertains to machines for producing battery separator plates.

It is the principal object of the present invention to provide a generally improved machine of the character referred to which is of simple and inexpensive construction, efficient in operation and having a greater capacity than prior machines of the same nature.

In carrying out this object into practice I provide a machine having a movable table carrying a knife for shearing slices from a billet of wood. The table is reciprocated both longitudinally and transversely during each stroke so as to obtain a shearing action of the knife on the wood. At each end of its stroke the table is moved to operative position relative to the billet of wood so that each stroke of the table will be productive.

One form which the invention may assume is exemplified in the following description and illustrated by way of example in the accompanying drawings, in which:

Fig. 1 is a plan view of a machine for slicing wood embodying the preferred form of my invention.

Fig. 2 is a side elevation of the same.

Fig. 3 is an end elevation of the machine.

Fig. 4 is a transverse section through the machine.

Referring more particularly to the accompanying drawings, 10 indicates a frame or base of a wood slicing machine which is particularly adapted for the production of battery separator plates. The machine, however, is capable of use in slicing wood for various other purposes.

Vertically arranged on the base 10 are four columns 11. The upper ends of these columns are fitted with bearings 12 and at their lower ends they are formed with pads which are securely bolted or otherwise secured to the base 10. The columns 11 are arranged in pairs, the column of each pair being in transverse alignment. The bearings of each pair of columns reciprocably support a transverse member 14. The arrangement of the columns is such that the transverse members are dis-

posed in parallelism one at each end of the base and transversely of the latter.

Each member 14 is formed with a central section 15, the opposite ends of which terminate in trunnions 16 which are reciprocably mounted in the bearings 12. Extending between the transverse members is a pair of guides 17 which are arranged in parallelism longitudinally of the machine and at ninety degrees to the transverse member 14. The ends of the guides 17 are securely fixed in the central portions 15 of the transverse members 14. Thus, the guides 17 and the transverse members 14 are relatively rigid and in effect form a transversely reciprocable carriage.

Guided on the guides 17 for reciprocation longitudinally thereof is what I prefer to term a table 18. This table is formed with a bearing 19 at each corner which are slidably disposed on the guides 17 so that the table 18 may be reciprocated longitudinally of the guides.

In practice I may fix the guides 17 to the table 18 and have them slidably engage the transverse members 14. This, however, is a mere matter of design and comes within the scope of the appended claims.

The table 18 is formed with a centrally located longitudinal slot 18a at one side of which is arranged a knife 20. This knife extends parallel to the slot and has a cutting edge overlying the slot. The knife as illustrated in Fig. 4 lies at a slight angle to the horizontal and is clamped to the table in such a manner that it may be removed or adjusted. Slightly below the cutting edge of the knife and contiguous thereto is an adjustable pressure bar 21. The cutting edge of the knife 20 overlies this pressure bar 21 so that a block of wood disposed on the pressure bar portion of the table will be sliced by the cutting action of the knife.

To support a block of wood I provide a block holder 22 which is fixed to the frame and overlies the table. This block holder is formed with a vertically arranged magazine 23 which is adapted to receive blocks of wood to be sliced. The lower end of this magazine is open so that blocks of wood fed therein will pass vertically therethrough and rest

upon the table 18 exposing the lower end thereof to the cutting action of the knife 20. The blocks of wood may be fed downwardly through the magazine either by their own weight or by the provision of additional weight bearing thereon.

It will be noticed that the knife 20 lies in parallelism to the guides 17 and the longitudinal axis of the machine. It is intended, however, to reciprocate the carriage composed of the guides 17 and the transverse members 14 transversely while the table 18 is being reciprocated longitudinally. Thus, as the knife engages the block it will be fed transversely therethrough during each stroke.

To reciprocate the table I provide a drive shaft 24 which may be driven by a pulley or by a directly connected motor as desired. This drive shaft 24 is fitted with a bevel gear 25 which is in mesh with a bevel gear 25 keyed or otherwise secured on a vertically arranged table drive shaft 27. At its upper end the shaft 27 is fitted with a crank arm 28 carrying a crank pin 29. A connecting rod 30 is connected at one end to the crank pin 29 and at the other end to the table as indicated by the numeral 31. It is obvious that when the shaft 27 revolves that the crank pin 29 will revolve and through the medium of the connecting rod 30 impart reciprocation to the table 18.

Coincidently with the reciprocation of the table 18 the carriage which carries the table 18 is reciprocated transversely. This is accomplished as follows: A cam 32 is supported by the frame and is driven from the drive shaft 24 at twice the speed of the shaft 27. Cooperating with the cam 32 is a cam arm 33 one end of which is secured on a rock shaft 34 journaled on the base 10 and extending longitudinally thereof. The cam arm 33 at its other end is fitted with a cam roller 35 engaging a cam groove 36 in the cam 32. This groove is so formed that the shaft 34 will be rocked at the proper intervals. Secured at their lower ends to the shaft 34 are rocker arms 37 the upper ends of which are connected to the transverse members 14 as indicated in Fig. 3 of the drawings. When the machine is in operation the arms 37 oscillate transversely of the machine at the proper intervals to move the carriage and the table carried thereby transversely as the carriage is reciprocated longitudinally.

In operation of the device assuming that the parts of the machine are in the positions illustrated in Fig. 1 of the drawings, it will be seen that the table 18 is at the extremity of its outer stroke and that the carriage is over to the end of its stroke in the direction of the arrow B. As the crank arm 28 moves past dead center, the cam 32 commences functioning to gradually move the carriage in the direction of the arrow A as the table is being returned to starting position. Thus, the knife

20 will pass through the block with a shearing action, shearing a slice of wood from the lower end of the block. This slice of wood as it is sheared passes between the knife and the pressure bar 21 and discharges.

When the table 18 is moved to the full extent of its return stroke, the carriage will be at the end of its stroke in the direction of the arrow A in Fig. 1 and the knife will have passed completely through the block of wood supported in the magazine 23. The formation of the cam groove is such that when this position is reached the carriage will be quickly moved transversely in the direction of the arrow B to return it to operative position for a successive operation and when the carriage commences moving in the direction of the arrow D the carriage will be gradually moved in the direction of the arrow A, so that the knife will again pass through the block and slice it. When the carriage reaches the outer end of its stroke in the direction of the arrow D, the cam again moves the carriage rapidly in the direction of the arrow B to place the knife in position for a successive cut and allow the block in the magazine to lower and engage the pressure bar portion of the table.

From the foregoing it is obvious that by means of this machine each stroke of the table 18 is productive. This is of importance as it makes the machine one of large capacity. It is also apparent that the construction of the machine is very simple and that it will be comparatively inexpensive to manufacture.

While I have shown the preferred form of my invention, it is to be understood that various changes may be made in its construction by those skilled in the art without departing from the spirit of the invention as defined in the appended claims.

Having thus described my invention, what I claim and desire to secure by Letters Patent is:

1. A machine of the character described comprising a reciprocable table, a slicing knife carried by the table, means for supporting material to be sliced relative to the table, means for feeding the table in two directions simultaneously to cause the knife to shear through the material, and means for returning the table to operative position at each end of its stroke whereby the knife will shear through the material twice during each cycle of operation of the table.

2. A machine of the character described comprising a base, a carriage mounted on the base for transverse reciprocation, a table mounted on the carriage for longitudinal reciprocation, means for supporting a billet of material relative to the table, a knife carried by the table, means for reciprocating the table and the carriage simultaneously in timed relation whereby to cause the knife

to move longitudinally and transversely through the material during each stroke of the table.

3. A machine of the character described comprising a base, a carriage mounted on the base for transverse reciprocation, a table reciprocably mounted on the carriage for longitudinal reciprocation, a knife arranged longitudinally of the table and carried thereby, means for supporting a billet of material, said means overlying the table whereby the billet of material will rest on the table, means for reciprocating the table longitudinally relative to the material, and means for simultaneously moving the carriage to feed the knife through the material as it advances therethrough.

4. A machine of the character described comprising a base, a carriage mounted on the base and adapted to be reciprocated transversely, a table mounted on the carriage for reciprocation longitudinally, a knife on the table and arranged longitudinally thereof, means for supporting a billet of wood in a position overlying the table whereby it will bear on the table, means for operating the table and the carriage in synchronism whereby the knife will advance longitudinally and transversely through the work on each stroke thereof.
